UNITED STATES PATENT OFFICE

WILLIS J. PERKINS, OF GRAND RAPIDS, MICHIGAN, ASSIGNOR TO WILLIS B. PERKINS, JR., AND BURGESS M. KIDDER, BOTH OF GRAND RAPIDS, MICHIGAN

AIRPLANE LANDING AND LAUNCHING APPLIANCE

Application filed March 23, 1931. Serial No. 524,547.

This invention relates to the providing of means for the landing, checking and stopping of all types of planes in areas of limited extent, also for their storage and take-off therefrom, and is concerned with many improvements over the landing and launching apparatus shown in my patent of December 3rd, 1929, No. 1,738,261 and application Ser. No. 581,659, filed August 14th, 1922, respectively, and other previous applications whose subject matter in part has been consolidated in this and said above identified patent and, pending applications. The serial numbers and filing dates of said previous applications are as follows: 180,787, filed July 16th, 1917; 192,101, filed Sept. 19th, 1917; 322,897, filed Sept. 10, 1919; 327,238, filed Sept. 29th, 1919; and 486,971, filed June 23rd, 1921.

A major object of this invention is to provide means whereby airplanes and hydroplanes of all types, may be landed on and started off of, and stored in a superstructure of limited area, erected above large buildings, as hotels, office buildings, post-offices, etc.; also above conventional public and private aerodromes, also above bridges spanning rivers, also above viaducts spanning railroad yards, also above intersecting highways, etc., thereby eliminating the necessity, relatively, of large aviation fields, and securing the landing of planes, passengers, and cargoes, at or near their objective, also on commercial and military ships of suitable size and through direct ship landing and takeoff eliminating the necessity of special aircraft carriers and catapults.

A further object is the application of electrical means for: (A) Checking and stopping an airplane after its pilot has negotiated a mid-air, trapeze hooking on landing. (B) Accelerating an airplane to flight speed, at flight altitude, free of all obstructions. (C) Automatic and manual control of the electrical operating means. (D) Automatically or manually, by such electrical means, maintaining the equipment in relation to the wind, so the plane always lands on and takes off therefrom, facing the wind. (E) Lowering plane from trapeze to aerodrome floor

level, and elevating same for attaching to trolley for take-off, while preventing plane, from being whipped around by the wind. (F) Automatically maintaining a non-resisting or balanced trolley on the upper 55 catenary curve of the trolley supporting cable. (G) Automatically applying a plane decelerating force to trolley after trolley's static inertia has been overcome by the plane's momentum. (H) Automatically increasing application of both decelerating and accelerating electrical power, as plane is slowed up in stopping and as plane's speed increases in take-off. (I) Automatically 60 checking and stopping the trolley after the plane is automatically shoved off therefrom. (J) Manually handling trolley as its service requires. (K) Raising and lowering wind shield provided while plane's wings 65 are disconnected from or attached to fuselage. (L) Operating an elevator between the floors of the aerodrome. (M) Opening and closing a hatch in roof of aerodrome to provide access to and from the elevator in 70 the aerodrome. 75

A further object is to remove the trapeze from the trolley when the trolley is used for launching plane and to maintain the trapeze in a non-interfering position until replaced on trolley. 80

A further object is to produce both a trapeze and a trolley of minimum weight and maximum strength and efficiency. A further object is to minimize the number of attendants required to operate the system, through concentration of all control at a single station. 85

A further major object of this invention is the substitution of a movable, endless, 90 electrically driven cable, for the stationary cable or track shown in my referred to previous application, and Patent No. 1,738,261.

A further object is to provide a superior electric control line and support for means thereof, said means coordinating with means located on the trolley carriage.

Other objects of the invention will appear more fully hereinafter.

These objects and purposes, above stated, together with many others not at this time 100

specifically outlined, and novel construction for attaining the same will be apparent, as an understanding of the invention is had from the following description, taken in connection with the accompanying drawings, in which,

Fig. 1 is an elevation of the construction embodying the airplane landing, checking and stopping and launching apparatus of my invention in association with and rotatably mounted upon an aerodrome equipped with a plane elevator.

Fig. 2 is a view similar to Fig. 1 showing the apparatus used for launching or take-off, wherein in Fig. 1 it is used for landing the plane, and with illustration of details for revolving the structure mounted on the aerodrome and other construction required in making operation and use of the invention practical and possible.

Fig. 3 is a plan view.

Fig. 4 is an end elevation with certain parts of the construction broken away and shown in section.

Fig. 5 is a fragmentary plan view of the aerodrome on line 5—5 of Fig. 1, showing the elevator for the handling of the planes and also plane wings and fuselages parked in area provided.

Fig. 6 is a side elevation of the fuselages as truck grouped in Fig. 5.

Figs. 7 and 8 are, respectively, an end elevation and a side elevation of the special fuselage truck.

Fig. 9 is a diagrammatic plan of the automatic and manually operated electrical apparatus utilized for turning the superstructure mounted on the aerodrome to different positions, so as to bring the landing and launching apparatus thereon in proper functioning position relative to the wind.

Fig. 10 is a fragmentary vertical section of one of the series of motor driven means for supporting and turning said superstructure about a vertical axis.

Fig. 11 is a fragmentary elevation, partly in section, of the adjustable wind break utilized when removing or assembling plane wings for storage or flight and electrical means for raising and lowering the sides and ends of said wind break, also elevation of plane handling elevator.

Fig. 12 is a fragmentary end elevation, partly in section, of the motor operated screw and its related nut and toggle connection for raising and lowering said wind-break members.

Fig. 13 is a fragmentary side elevation of Fig. 12.

Fig. 14 is a plan view of the elevator platform with the operating means located thereon, and the related supporting means, portions being omitted for clarity of illustration.

Fig. 15 is a fragmentary detail of the

motor driven mechanism for operating the elevator.

Fig. 16 is a fragmentary plan view of the elevator platform and plane parking floor with the elevator operating means shown in plan and horizontal sections.

Fig. 17 is a rear elevation of a preferred form of trapeze with the flexible landing platform or cable and automatic trolley lock and connections.

Fig. 18 is a plan view of said trapeze on line 18—18 of Fig. 17.

Fig. 19 is a fragmentary enlarged plan of one end of said trapeze.

Fig. 20 is a fragmentary end elevation of the automatic lock and detachable means used for connecting and locking said trapeze or disconnecting it from its supporting movable trolley.

Fig. 21 is a rear elevation of the construction shown in Fig. 20.

Fig. 22 is a plan view thereof, a portion of the automatic trapeze and trolley locking means being broken away and shown in section in both locked and unlocked position.

Figs. 23 and 24 are, respectively, a plan and side elevation of a portion of the means manually operated for attaching to and detaching the said trapeze from the trolley.

Fig. 25 is a side elevation of the flight controllers or operators platform on which are grouped the various electrical and manual controls required for the system's efficiency together with the electrically driven cable wheel and motors, with a fragment of the trolley supporting and operating cable, and fragment of said cable's and trolley's control lines.

Fig. 26 is a plan view of the construction illustrated in Fig. 25, showing more clearly the electrical and manual controls provided.

Fig. 27 is a front elevation of the structure shown in Figs. 25 and 26 with certain parts of the same in section.

Fig. 28 is a front elevation of one of the two part members used in mounting the bumper springs against which the trolley may engage at the opposite ends of its movement.

Fig. 29 is a side elevation of the cable and the wiring used in direct conjunction therewith.

Fig. 29a is a diagrammatic view of the electrical wiring and controls for automatically and manually controlling the speed and direction of travel of the trolley supporting cable at the different stages of the operation thereof in landing and launching airplanes on and off the trolley (not shown) mounted on said cable and its related trapeze (not shown) together with the trips located on the control line, for automatically operating the cable gripping clutches and the plane's take-off releasing means as related to said trolley.

Fig. 30 is a side elevation of the trapeze engaging landing hooks and automatic lock and automatic engine ignition cut-out switch carried by all aeroplanes which are landed and launched with the apparatus of my invention.

Fig. 31 is a fragmentary enlarged side elevation and cross section on line $x-x$ of Fig. 31, of said hook, illustrating the details of construction thereof.

Fig. 32 is a fragmentary vertical elevation and section through the joint between the two parts of the construction showing the elevating cable hooked therewith, the section being on the line $y-y$ of Fig. 31.

Fig. 33 is a fragmentary side elevation showing said joint in the position it occupies when an airplane has landed and has come to rest on the trapeze platform and supported on the elevator cables.

Fig. 34 is a horizontal section substantially on the plane of line 34-34 of Fig. 31.

Fig. 35 is a front side elevation showing the trolley carriage carried on fragmentary sections of the supporting cable for carrying and accelerating the airplane, a fragmentary section being shown attached thereto, said carriage also being adapted to support and carry the trapeze landing platform.

Fig. 36 is a similar elevation from the opposite side.

Fig. 36a is a horizontal fragmentary section through said carriage below the plane of line 36-36 of Fig. 36, the wing section being omitted.

Fig. 36b is a fragmentary enlarged side elevation, similar to Fig. 36, with the trolley locking parts in a releasing position.

Fig. 37 is a plan view of the trolley carriage with certain parts broken away for a better disclosure.

Fig. 38 is a front end elevation and section substantially on the plane of line 38-38.

Fig. 39 is a vertical rear end elevation partly in section on the plane of the lines 39-39 of Fig. 35 and Fig. 40.

Fig. 39a is a projected side elevation of certain of the related parts shown in Figs. 36 and 39.

Fig. 39b is an enlarged fragmentary elevation of the slidable bar shown in Fig. 39a with clutch gripping spring attached.

Fig. 40 is a horizontal section substantially on the plane of line 40-40 of Fig. 39, looking down on a fragment of a plane wing.

Fig. 41 is a fragmentary enlarged side elevation and partial vertical section illustrating the latch control means for manually connecting the airplane to and automatically releasing it from the trolley carriage.

Fig. 42 is a fragmentary front elevation of the mechanism shown in Fig. 41.

Fig. 43 is a fragmentary front elevation of the rear member of the latch mechanism

for connecting the airplane to and releasing it from the trolley.

Fig. 44 is a fragmentary enlarged side elevation of the automatic mechanism utilized for releasing the latch and freeing the airplane and operating the cable clutch on the trolley; also for carrying the electric control line and coordinating trips.

Figs. 44a and 44b show fragmentary portions and like sections at different parts in the length of the electric line adjacent the trips T1 and T2 respectively.

Fig. 45 is a fragmentary enlarged horizontal section and plan view of Fig. 44.

Fig. 46 is a fragmentary vertical section showing details of the construction shown in Fig. 44.

Figs. 47, 48 and 49 and 50 are fragmentary horizontal sections and plan views of the mechanism located immediately above the forward trolley latch and which is initially manually operated and later automatically operated at predetermined distances in the movement of the trolley carriage in relation to the control line, for the purpose of automatically releasing the plane attached thereto at a predetermined distance from the flight controller's platform and simultaneously releasing the top cable clutch and applying the bottom cable clutch.

Fig. 51 is a fragmentary side elevation of the construction shown in Fig. 50.

Fig. 51a is an elevation of a detail of the structure shown in Fig. 50, comprising a collar and attached trip.

Fig. 52 is a fragmentary detailed horizontal section and plan view illustrating the supporting frame mechanism for the devices shown in Figs. 47 to 51 inclusive.

Fig. 53 is a plan view of the means located on the rear portion of the trolley carriage for locking open and trip releasing the upper cable clutch, the action being as further shown in Fig. 40, and with the parts located in the same position with the control line in related position thereto.

Fig. 53a is a like view with the parts in a different position with the trip and the clutch releasing means in an inoperative adjustment.

Fig. 54 is a like view, the parts having been automatically trip operated to a still further different position.

Fig. 55 is a rear elevation of the construction shown in Figs. 53, 53a and 54.

Fig. 56 is an end view, partly in cross section as indicated by the line 56-56 of Fig. 55.

Fig. 57 is a view taken along the plane of line 57-57 of Fig. 55.

Fig. 58 is an enlarged plan view of the clutch used to grip the cable at the top of the trolley carriage.

Fig. 58a is a transverse section through Fig. 58.

Fig. 59 is a plan view of the cable clutch at the bottom of the trolley carriage.

Fig. 60 is a side elevation of the flight controller's platform and of the trolley carriage and the trapeze suspended therefrom, with a means pivoted on the flight controller's platform for holding the trapeze against backward movement when in operative position and in the path of movement of the plane-landing hook, as shown, and for holding it in retracted horizontal position when the trolley is used for plane's take-off.

Fig. 61 is a front view of the construction shown in Fig. 60.

Fig. 62 is a fragmentary enlarged front elevation and partial section of the trapeze stabilizing means, and,

Fig. 63 is a side elevation thereof.

Like reference characters refer to like parts in the different figures of the drawings.

The landing and launching or take-off apparatus of my invention, in one of many places of use thereof is at the top of an aerodrome 1 of cylindrical form having a cover 2 or roof 2 thereover rotatable about a vertical axis. To this end a plurality of shafts 3 are located inside of the aerodrome and suitably mounted in supporting brackets 4 carried by the cover 2, and on each shaft is a flanged wheel 5 riding on the upper end of the walls of the aerodrome which serve as tracks for the wheels; or a suitable track may be mounted thereon.

Each shaft carries a worm gear 6. Adjacent each of the wheels 5 is an electric motor 7 having a worm 8 meshing with its adjacent tangent wheel 6. The motor is carried on a base 9 which is preferably formed integral with the support 4 carrying each shaft 3, it being evident that when the motors are all in operation the shafts are turned and the covering member or roof 2 of the aerodrome may be turned to different positions about a vertical axis on the walls of the aerodrome.

The motors are all connected in parallel by wires 10 and 11 from which branch wires 10a and 11a extend to the motors 7 (see Fig. 9). Two spaced apart contact shoes 12 and 13 are connected with the wires 11 and 10 respectively by wires 14 and 15, as shown, while other spaced apart contact shoes 16 and 17 are similarly connected to the wires 11 and 10 by connecting wires 18 and 19. The shoes 12, 13, 16 and 17 are in arcs of circles and are spaced apart a distance at their adjacent ends. A switch arm 20 is pivotally mounted on a vertical axis 21 carried by the superstructure 22 mounted on the cover or top 2, as will later appear, extending to one side of the axis 21, while the diametrically opposed side is formed with a vane 22 whereby the wind will swing the vane so as to point the swinging arm 20 in the direc-

tion of the wind. The contacts 23 and 24 are carried on the arm 20 so that the same will contact either with the shoes 12 and 13 or the shoes 16 and 17 when the vane is swung from a neutral position with respect to the shoes, the neutral position being shown in Fig. 9.

Two wires 25 and 26 lead from the contacts 23 and 24 respectively. The wire 26 is connected with the ground or negative side of any suitable electric circuit. The wire 27 leads from positive or plus side, it being understood that any suitable source of electric energy is included in the circuit, to a manually operable lever 28 which may swing over three spaced apart contact shoes 29, 30 and 31. The first shoe 29 is connected with the wire 25, previously described. The second shoe 30 is farthest away from the shoe 29 with the shoe 31 between. When the switch 28 is brought into contact with the shoe 29 an electric circuit is completed, or at least it is in readiness for completion should the wind swing the arm 20 so as to bring the contacts 23 and 24 into engagement with either the shoes 12 and 13 or shoes 16 and 17. When the lever 28 is at the middle position on the intermediate contact 31 no circuit is or can be completed.

It is evident when the vane 22 is in a position such that the switch arm 20 points into the wind and the upper structure carried on the top 2 is properly located with respect to the wind, the contacts 23 and 24 are neutrally located between the shoes described. A change in the direction of the wind swings the contacts 23 and 24 to one side or the other so as to complete one or the other of the circuits, providing the lever 28 is in engagement with the contact 29. When the contacts 23 and 24 engage with the shoes 12 and 13 the motors 7 are turned in one direction so as to turn the top 2 clockwise and position the contacts 23 and 24 again at a neutral position. If the change in the direction of the wind swings the contacts 23 and 24 to the opposite side, whereby they engage with the shoes 16 and 17, the motors 7 will turn in a reverse direction and turn the top 2 and the superstructure carried thereby counter-clockwise, (referring to Fig. 9) and again locate the contacts 23 and 24 at neutral. In other words, the mechanism described provides a continuous automatic control for the proper positioning of the top 2 and the superstructure hereafter described, carried by the top 2, shall be properly located with respect to the wind for landing and launching airplanes.

A wire 32 leads from the contact 30 and has a branch 33 therefrom, both the wires 32 and 33 ending with suitable contacts. A wire 34 leads from the wire 26 and likewise

has a branch 35, both wires 34 and 35 ending in contacts which are spaced apart the same as the contacts at the ends of the wires 32 and 33. Two wires 37 and 36 are connected with the wires 10 and 11 respectively. A branch 38 leads from the wire 37, both the wire 37 and its branch ending in spaced apart contacts. Another branch wire 39 leads from the wire 36, as shown in Fig. 9, both the wires 36 and 39 likewise ending in contacts. An H-shaped switch 40 is mounted for rotation so as to engage with the different contacts. In the full line position, shown in Fig. 9, one side of the switch connects those at the ends of wires 34 and 38. By swinging the switch to the position shown in dotted lines the first side of the switch noted will connect the wires 33 and 37 and the other side the wires 39 and 35. This construction is for manually controlling the position of the top 2 and the superstructure carried thereby. If the H-shaped switch 40 is in the position shown in full lines, swinging lever 28 to make electrical connection with the contact 30 will cause rotation of the various motors 7 in one direction irrespective of the direction of the wind; and if the switch 40 is in the other position shown in dotted lines, the direction of the 30 rotation of the motors will be in the opposite direction.

It is, therefore, evident that an automatic control of the position of the top 2 and the mechanism carried thereby will be had through a control exerted by the wind; while if this automatic control is not desired, as may be at times, the control and position of the cover 2 and the devices carried thereby may be governed by the operation of the 40 two switch members 28 and 40, while with the switch 28 at neutral position, as shown in full lines in Fig. 9, the table 2 is not subject to any change in position.

Substantially at the center of the top or 45 roof 2 of the aerodrome a rectangular opening is made, a retractable cover 41 being adapted to cover the opening at times. Said opening has a length and width such that the fuselage of an airplane may be passed 50 therethrough or two wings on a truck, as shown in Fig. 5. Side and end members 42 and 43 of an enclosing barricade are located a short distance from the ends of the opening and a considerable distance from the 55 sides of said opening being pivotally connected to the top 2 so that they may be swung from horizontal to vertical positions and vice versa, in their vertical position forming an enclosure in which an airplane may be 60 placed and wherein the wings of the plane may be removed from or attached to the fuselage without wind interference. The lifting or lowering of the members 42 and 43 is accomplished by means of bars 44 attached at one end to the sides and ends 42

and 43 and at their other ends extending through openings in the top 2. Horizontal shafts 45 (see Figs. 3 and 11) have gearing connection with screw threaded shafts 46 located in substantially the same plane with 70 each of the bars 44 connected with the members 42 and 43.

Gearing connections through shafts 47 are driven by the shafts 45 to serve to operate other threaded shafts 48 similar to shafts 75 46, located in the same plane with bars 44 connected with the members 43 (see Fig. 3). The shafts 45 are driven by electric motors 49 through worm gearing connections 50. An interiorly threaded sleeve or nut 51 is 80 mounted on each screw threaded shaft 46 and 48 to which the lower ends of the bars 44 are connected. Said bars 44 at their lower ends (see Figs. 12 and 13) are forked to pass to either side of the sleeve 51 and carry 85 rollers 52 which ride upon tracks 52a, it being evident that on operation of the motors 49 the sleeves 51 move on shafts 46 and 48 with a resultant lifting or lowering of the sides and ends 42 and 43 dependent upon 90 the direction of rotation of the motors; and said motors, being reversible, the side and end members 42 and 43 may be readily and safely raised or lowered as may be desired 95 irrespective of wind conditions.

The cover 41 for said opening in the top or roof 2 is designed to be moved from the position shown in full lines in Fig. 3 to that shown in dotted lines, or vice versa through a motor 41a driving gearing 41b, the underside of the cover 41 having a rack to engage with the gearing (see Fig. 2) for such movement. The opening is thus covered when planes are not being raised from or lowered to the aerodrome parking floors.

An elevator table or platform 53 is mounted in the aerodrome directly underneath the opening in the roof covered by the cover 41. Vertical posts 54 are located in spaced apart relation, each at its inner side carrying a vertical rack 55. The posts are connected and reinforced at their upper ends by a surrounding band 54a. A circular band 56 is attached to and forms portion of the elevator platform and is located interiorly of the posts 54 and racks 55 below the elevator table 53 and carries guide rollers 57 extending outwardly therefrom to ride on the backs of the racks 55 rigid with the posts 54. The table 53 is supported on and above said band. A plurality of radial shafts 58 extend at their outer ends through the band 56, being equipped with pinions 59 in meshing engagement with the racks 55. The inner ends of shafts 58 carry bevelled pinions 60 all meshing with a bevelled gear 61 which is mounted within a worm gear 62 driven by worms 63 fixed on the shaft of an electric motor 64, as shown in Fig. 15. The table 53 may therefore be raised and lowered on the racks 130

55 by operating the motor 64 in opposite directions and thus carry a fuselage and wings placed on the elevator table 53 from an upper position above the top 2 of the 5 aerodrome to a lower position to the same plane with the floor 65 of the aerodrome, (see Fig. 5). The three posts 54, as shown in Fig. 14, with attached racks, guides and pinions causing the elevator platform when 10 raised or lowered to be maintained level and dispensing largely with the conventional guides, uprights and well, commonly used with elevators, three racks, as used, are particularly practical, two being impractical 15 and four or more unnecessarily restricting the passage on and off of the elevator platform.

The fuselage of an airplane, indicated at 66 in Fig. 6, is adapted to be carried on a 20 truck 67 formed at its opposite ends with upwardly extending supporting members 68 and 69 for said fuselage. The wings 70 of the plane are detachable. The planes may be stored in the aerodrome mounted on the 25 trucks for ready placing on the elevator table or platform to lift to an upper position level with the top or roof of the aerodrome where the wings may be attached within the 30 protecting wind break afforded by the side and end members 42 and 43. It is evident that the aerodrome will hold a large number of planes with the wings and fuselages thereof separately stored so as to have an economy of space, as illustrated in Fig. 5.

35 It is designed that an airplane landing and launching apparatus shall be mounted on and above the top or roof 2 of the aerodrome, revolving therewith in its turning movements. A vertical post 71 extends upwardly and curves over the center of the table from one side of the top or roof 2 forming a semi-arch truss. Supporting beams or trusses 72 of suitable metal construction extend horizontally outward from 40 the table 2 and at their outer ends carry other posts 73 which extend upwardly and are curved over the top 2, as best shown in Fig. 4, to provide other semi-arch trusses. The supporting posts 71 and 73 are reinforced by vertical bracing posts 71a and 73a with horizontal ties connecting the upper 45 ends thereof with the supports 71 and 73. Beams or trusses 74 connect the upper ends of the supports 71 and 73, (see Fig. 2.) forming a supporting frame work for the apparatus mounted thereon.

The construction described forms a support for an endless electrically driven cable which supports a trolley carriage mounted 60 on the cable on which the plane landing and take-off equipment alternately function. It also supports the cable speed control line with its attached plane release trips and rheostat speed control of cable speed and 65 the operator or flight controller's platform,

and in addition therewith, the elevator equipment for lowering landed planes and for raising planes for attachment to the trolley preliminary to their take-off. The cable is located a considerable distance 70 above the top 2 of the aerodrome and there is an open space at the sides of the supporting posts 71 and 73 and underneath the connecting truss 74 for the entrance of an airplane when it is to be landed or for its 75 passage when it is to be launched (see Fig. 4). Near the upper ends of each of the end supporting posts 73 a large pulley 75 is mounted for rotation, and endless cable 76 being supported thereon and driven thereby. Between the upper and lower runs of the cable is an elongated electric trolley control line 77 comprising an upper metal bar 77a, (see Figs. 29 and 29a), a lower metal bar 77b and an intermediate metal bar 77c 80 suitably insulated from each other with insulation indicated at 78, 78c and 78d for automatically controlling the variable planes' decelerating and accelerating speed of the trolley and plane supporting cable. 85

The airplane at its upper side on a wing attached thereto has engaging members 80 thereon with which the trolley carriage 79 is detachably hooked for launching purposes (see Figs. 2, 35, and 36). The trolley carriage 79 is movable by an endless cable 76 between the two pulleys 75, and suitable buffer springs 81 are supplied at each end of the run to take up any shock of stopping at the ends of the run. The springs 81 have 90 suitable sockets 81a on members 81b at the ends of the supporting posts 73, (see Figs. 27 and 28).

Included in the construction of the trolley carriage 79 are tubes 82 converging at 105 their upper ends and connected by a cross tubular member 83. (See Figs. 20, 21, 35 to 40.) The tubular member 83 projects outwardly at each end to furnish a support for a trapeze landing platform construction (see Fig. 17) adapted to be detachably hooked on the ends of said tubular support (see Fig. 4).

In the construction of the trapeze landing platform, (Fig. 17), two spaced apart hook members 84 are provided, (Figs. 20 and 22) each of which at its lower end is equipped with a pulley 85 over which a line or cable 86 is passed. The trapeze landing platform extends transversely underneath the trolley carriage 79 and is designed to be located in substantially the same vertical plane as the tubular supporting bar 83. The pulleys 85 are likewise located in substantially the same vertical plane and when the cables are passed thereover the inner lengths of the cables extend vertically downward. The outer lengths or runs of the cable extend downwardly and outwardly to and around the ends of a substantially horizon- 115 120 125 130

tal rigid supporting structure consisting of a plurality of connected tubular bars 87 equipped with pulleys 88 at its ends, around which the cables 86 pass. (See Fig. 17.)

5 At the ends of the upper rigid structure, made by the bars 87, are shafts for supporting the pulleys 88 on which are mounted side members 89 of the trapeze landing platform. Said members are pivotally mounted between their ends having parts extending above the shafts 88, each formed at its upper end with an arc shaped part 90 to which the ends of cables 86, after passing around the pulleys 88, are secured, the 10 same passing through suitable guides 91. As shown in Fig. 17 the parts 90 are substantially arc shaped receivers for the ends of the cables 86 attached thereto which are held in place thereby and between guides 20 91 and also by suitable guides 92 adjacent the pulleys 88. The immediate flexible landing platform member 93 is a cable, preferably, attached at its ends to the ends of the rigid horizontal bar construction 87 and 25 passing downwardly through suitable guides at the lower ends of the pivoted side members 89. Midway between the lower ends of said member 89 the landing member 83 may be equipped with a downwardly recessed stiff member 94 into which the landing hooks of the airplane eventually seat upon landing on the trapeze landing platform for the purpose of preventing sagging 30 of the landing platform and stop any crowding of the landing hooks toward each other. A fixed collar 95 may be secured to the outer length of each of the trapeze supporting cables 86 a distance above the arc shaped member 90 and below is a movable 35 40 collar 96, while between the two collars is a coiled compression spring 97. The inner vertical sections or lengths of the cable 86 are permanently secured to the bars 87 by diverging cords 98, four being shown for 45 each cable 86 and connected at their lower ends to the rigid bar construction 87. See Fig. 18.

It is evident that when an airplane connects with the trapeze landing platform by 50 hooking over the immediate engaging member 93, said member on account of the weight of the plane thereof sags at its middle pulling the lower ends of members 89 toward each other drawing on the cables 86 and 55 bringing the collar 96 against the upper parts 90, (see Fig. 17) of said swinging members 89, and simultaneously lifting the entire trapeze landing platform and plane attached thereto vertically whereby is a 60 cushioning and absorption of the force of landing of the plane on the trapeze landing platform with a minimum shock and strain on all related parts the function of the same duplicating the action of the firemen's net, 65 which admittedly constitutes the best known

physical means for arresting a vertically falling body while the upward swing of the plane, and trapeze is evidently the best physical means for checking and stopping a horizontally moving body.

The trapeze landing platform 93 is to be supported on the trolley carriage 79 only when the airplane is being landed thereon and must be disconnected therefrom, and held out of the way (see dotted lines, Fig. 60) when the take-off of the plane is to be cared for. To this end, each of the hook members 84 (see Figs. 20 and 21) is supplied with latching means which may be operated by the flight controller through means provided, to either disconnect and remove or replace and connect the trapeze landing platform on the trolley carriage.

To the upper side of each hook member 84 a ring 99 is permanently connected, disposed in a plane at right angles to the plane of the hook member 84 at one side of which is a forwardly extending section 100 of a cone, which is completed at the other side by a complementary cone section 101. The section 100 is integral with the ring 99 while the conical section 101 is fixed to horizontal bars 102 extending outwardly and having hinged connection to other bars 103 permanently secured to and extending outwardly from the ring 99. A hinge pin 104 extends through the adjoining ends of the bars 102 and 103, there being a coiled spring 105 around the hinge pin, one end of which bears against one of the arms 103 and the other end against the cone section 101. It is evident, therefore, that the section 101 may swing away from the ring 99 but is normally held thereagainst by the spring 105.

A latching device 106 is integrally formed with and extends downwardly from the lower arm 102 described, being of concaved shape at its rear side to come in front of the end of the tubular bar 83, previously described, thereby serving to hold the hook 84 associated therewith in engagement with the end of the bar 83; but by swinging the section 101 away from the ring 99 the latching member 106 is moved away from the end of the bar 83 with which it normally engages, thus freeing the hook 84 so it can be readily lifted from engagement with said bar 83.

At what may be termed the operating end of the apparatus, that is, at the left in Figs. 1, 2, 3, 25, 26, 27, 60 and 61, a U-shaped tube 107 is mounted for turning movement on a horizontal axis, the two legs of the member extending in the direction of the cable 76 and being equipped at their free ends with fingers 108, (see Figs. 22, 23 and 24) having upturned ends, while each of the legs of the member 107 at its outer end has an upwardly extending stop 109. When the trolley carriage 79 is at the left of the ap-

paratus, the fingers 108 may be aligned by the attendant by use of means provided therefor to bear against the conical sections 101 and force the same outwardly so as to disengage the latch members 106 from the tubular rod 103. An arm 107a (see Fig. 25) extends downwardly from the U-shaped member 107 engaging against which is one end of a screw 107b with a hand wheel 107c at its other end, whereby the legs of the U-shaped member 107 may be tilted upwardly to lift the trapeze perch out of engagement with the trolley carriage, or may be lowered to thereby engage the trapeze landing platform with the trolley carriage.

At the operating end of the apparatus a platform P is positioned on which the flight controller is to stand when the equipment is in service. The various electric and other control devices which need to be manually operated are all within reach of the flight controller or attendant when on the platform during the operation of landing planes or of launching or raising and lowering the same, all of which will hereinafter appear upon description of the operation of the apparatus.

Two spring elevated landing hooks 110 are attached to a shaft extending through the fuselage, said hooks being normally stream-lined on opposite sides of the fuselage. A spring, acting on said shaft, causes the hooks 110, to be elevated in position as shown in Figure 1, upon the pilot releasing a lever which normally holding them stream-lined. The pilot releases said hooks just prior to making a hooking-on landing on the trapeze landing platform 93, the control and functioning of the landing hooks being substantially the same as shown and described in my patent of December 3, 1929, No. 1,738,261. (See Figs. 1, 2, 4, 30-34). Said landing hooks, when thus spring elevated, may extend 10 ft. more or less above plane's wing and propeller, such extension, securing proportionately, a vertical leeway for the pilot to make his hooking-on landing on the trapeze platform, 93. Irrespective of where the shank of the hook engages with platform 93, the forward flight of the plane, causes the platform 93 to slide up the shank 110-B until it reaches the hook and enters the opening where it strikes the spring operated pivoted arm 141 (see dotted lines, Fig. 31) lifting the same off lug 136-A, when spring, 137, rotates locking arm 133 on its pivot, 134, until the same is arrested by stop 136, thereby locking plane securely to trapeze landing platform 93.

The middle supporting semi-arch 71 at its upper end carries two drums 111 (see Fig. 4) which may be operated through worm gearing, indicated at 112 by an electric motor 113 in either direction, the switch control being located on the flight

control platform (Fig. 26). Cables 114 are wound around the drums and are adapted to be attached to an airplane midway of their lengths for lifting the same upwardly to engage with the trolley carriage 79 or for lowering the same to the elevator 53 through the opening 41.

After the plane has been landed, the trolley may be carried back to a position over the disassembling floor 41, the lines 114 engaging therewith and extended for snubbing action through the floor or cover 41, the landing hooks disconnected from the trapeze landing platform, the plane lowered and disassembled and then lowered by the elevator to the aerodrome. For launching or taking-off the plane is first elevated from the aerodrome and assembled within the surrounding wind break members 42 and 43 and then lifted by the cables 114 wound around drums 11, all within the control of the attendant, and the connecting members 80 on the plane engaged with the trolley carriage as shown in Figs. 35 and 36.

The pulleys 75 which carry the cables 76 have gears 116 connected therewith, driven by a plurality of electric motors 117, (see Figs. 25, 26 and 27) the shafts of which are equipped with pinions 118 meshing with said gear. The pulleys 75, motors and the shafts and the like, are mounted on a suitable support 119 of circular form and wheel-like in shape carried at the upper ends of the supporting posts 73.

In Fig. 29 is a diagrammatic outline of the electrical control means for the cable speed and direction of travel and control of the cable clutches on the trolley is shown. The switch 120, which is manually operable, is mounted within reach of the operator on the platform P (see Fig. 26). A distributing switch 121 and a reversing switch 122 are also located in place for each access as are also the automatic plane acceleration and plane deceleration switches 123 and 124. The wiring illustrated in Figs. 29 and 29a and the manner in which the rheostats are operated will be later described after an understanding of the other necessary constructions of the invention is had.

At a point above the control means 77 at its left (see Figs. 25 and 26) a horizontal pivoted shaft 126 is journaled. Said member 125 extends forward and carries the guide rollers 125a, and also has formed integral therewith the cable clutch releasing incline 125b and the trolley locking catch 125c. (The purpose of this device is to hold the trolley against the traction of the speed-ing cable in the take-off of the plane while the pilot is warming up and testing the motor; also to open and hold open the cable clutch so that the cable may run freely until the flight controller releases the trolley for the plane's take-off. Also, this device opens

the cable clutch so that it may be caught and held open while the plane is landing on the trapeze platform by means of the devices hereafter described and the details of 5 which are shown in Figs. 35, 36, 40, 44, 53-57 the cable clutch releasing automatically when the catch 262 on the trolley engages with the trip "A", see Figs. 1 and 2, and 1², see Figs. 29 and 29a.

10 An operating handle 127 extends to the rear and is engaged with a notched arc 128 so that the member 128 may be moved to different position. A contact arm 130 is secured to and extends downwardly from the 15 end arm 107a previously described between two electrical contact members 130a and 130b of a switch to automatically light an electric signal light when the trapeze platform has been removed from the trolley preparatory 20 to attaching a plane thereto for its take-off.

A horizontal rock shaft 301 (Figs. 35 and 38) is mounted at the upper part and adjacent one side of the trolley from which the 25 depending arm 262, previously described, extends to one side and downwardly so that its lower end may be positioned adjacent the bar 255, see Figs. 38 and 53. Said shaft 301 has a second arm 302 mounted thereon at 30 one end as shown in Fig. 35, also extending downwardly, and in a position such that when the trolley is brought adjacent the flight control platform it rides on the incline 125b, see Fig. 26, and thereby automatically 35 turns on the incline 125b and thereby automatically turns on the shaft 301 so as to move the arm 262 from the dotted to the full line position shown in Figs. 38, 53 and 55.

40 The landing hook construction which is applied to the airplane is illustrated in detail in Figs. 30 to 34 inclusive. The members are attached at their lower ends in advance of the center of gravity of the plane 45 to a spring and lever operated rock shaft extending through the fuselage and forming their pivotal support at each side of the fuselage as appears fully in my said Patent No. 1,738,261. Said members are divided into 50 two sections 110a and 110b pivotally connected at their meeting ends. A cable 131 is attached to the outer end of each of the lower sections 110a leading back to any suitable spring actuated winding drum attached 55 to the fuselage aft of the center of gravity of the plane which normally tends to return wind the cables when the pilot stream-lines the hooks by a lever operation against the tension of the elevating spring. To the upper ends of the outer sections 110b a hook 60 132 with integrally formed cable locking means 113 same being pivotally mounted on the pivot 134 (see Fig. 31). The locking member 133 is of irregular shape and at its lower end terminates in an arm 135 which

is held by spring 137 against a stop 136 when the plane is suspended on the landing platform 93. The hooks 132 at their inner sides each carry a concaved and curved connecting member 132b into which the flexible landing platform 93 is adapted to fit when the hooks have connected with said landing platform, said member 132b preventing hook members 132 from being forced toward each other by pressure from sag of the platform 93. A coiled torsion spring 137 is located around the pivot 134 and acts on the latch 133 to normally move it into engagement with the stop 136.

An operating cord 138 is connected to the lock member 133, leads over idler pulley 139 and is equipped with a ring 140 at its free end, whereby by engaging with said ring and pulling thereon the latch member may be pulled back to the dotted line position, shown in Fig. 31, and open the hook for the removal of the plane from the trapeze landing platform member 93. A latch bar 141 is pivotally mounted at the forward edge of the hook 132 and a spring 141a serves to turn the latch bar 141 in a downward direction when the member 133 is moved to the dotted line position shown in Fig. 31, the free end of the latch bar engaging with the lug 136a and holding the member 133 in the position to which it is moved, whereby the hook is opened for a second landing engagement with the trapeze landing platform. A contact member 142 is mounted on the upper portion of the hook member, adjacent which is a fixed support 143 on which a second spring contact 144 is secured, wires 145 leading from the contact 142 and support 143 to the engine of the airplane and forming a part of the ignition circuit, which is automatically closed by the depending end portion 135 of the member 133 coming against the upper end of the spring contact 144 and moving it to the dotted line position shown in Fig. 31 when the ring 140 is engaged and the member 133 drawn back and latched in the dotted line position shown in Fig. 31, thereby manually cutting in engine's ignition system and automatically cutting it out at instant of plane's landing.

The two members 110a and 110b of the hook structure, one of which is mounted at each side of the airplane fuselage, are pivotally connected together at their adjacent ends. A ring joint 146 has connected thereto at opposite sides other rings 147 which overlap, at their outer edges, the inner edges of members 148, which are secured at the upper and lower ends of the parts 110a and 110b, as shown in the cross section appearing in Fig. 31. This provides a pivotal connection of the two parts. The connected rings 146 and 147 are held against rotation by a spring 150 mounted upon the member 110a which engages in notches 149 in the

- rings 147 and bears against a projection 151 of the center ring 146, whereby the inwardly projecting sector 146a of the center ring 146 is spring held against turning movement by 5 a stop 146b on members 148. The cables 114 which are used in raising and lowering the plane are provided with sleeves 153 held by the collars 152 and having hooks at their sides to pass through the rings 146 and 147, 10 the inwardly projecting sector 146a seating in the bottom of the hook as shown in Fig. 32. The location of the hook members on the fuselage is such that when the plane is raised and lowered with the lower section 15 110a extending upwardly and back of the upper wing of the plane, the center of gravity of the airplane is in the same vertical plane with the raising and lowering cables 114.
- 20 It is evident from the foregoing that during flight of a plane, the members 143 will be pulled back and latched in the dotted line position, shown in Fig. 31, whereby the ignition circuit will be completed and that as 25 soon as the landing hooks engage with the lower member 93 of the trapeze landing platform when said lower member enters the open hooks it will engage against the under sides of the latch bars 141, turning them to 30 the full line position shown in Fig. 31, releasing members 133 and automatically breaking the engine ignition circuit, whereupon the engine will stop, this occurring the instant that the hooks engage with the 35 trapeze landing platform, also thereby locking the plane to the landing platform. It is of course, to be understood that the hook members during the flight of the plane are to lie alongside the body of the fuselage in 40 stream line relation thereto, being drawn down and locked to such position during flight, but released for spring elevation to their upper operative position a short time prior to landing on the trapeze landing platform by use of the same or similar construction to that shown in my Patent No. 1,738,261, 45 previously referred to.
- The operator's platform P at its under side preferably, is equipped with sills, such 50 as I-beams 156 (see Figs. 62 and 63), to the under side of which at the inner end of the platform inverted U-shaped brackets 157 are firmly secured to which other U-shaped brackets 158 are pivotally connected, the 55 two brackets being provided with complementary stops 159 and 160 (Fig. 63). A bar 162 extends downwardly from each of the brackets 158 and in the preferred form of construction, shown in Figs. 61, 62, and 60 63, a cross tube 163 connects the lower ends of the tubular bars 162, it being a pivotal joint connection, illustrated at 164, utilized for such connection, and for the further connection of the upper ends of other pending bars 165 to turn about pivots 166,

the tubular bars 165 lying in substantial alignment with the tubular bars 162 but capable of pivotal movement about the axis of the pivots 166. Two spaced apart hooks 167 and 168 extended outwardly from the 70 tubular bars 165 and are then turned downwardly forming hooks at their underside.

Cables 169 are attached to the cross tube 163 and lead therefrom to and around cable drums 170 at the ends of a horizontal shaft 75 171 suitably mounted for rotation above the outer portion of the platform P. The shaft 171 is driven by an electric motor 172 through suitable interposed gearing 173 whereby the structure may be swung from 80 the full line operative position, shown in Fig. 60, to the upper dotted line position where it is held out of the way of the plane when it takes off by holding hook 174 from which it may be disengaged for lowering to 85 the full line position.

As previously described, the trapeze landing platform is suspended from the trolley carriage when an airplane is to be landed but is lifted off the trolley carriage by the 90 U-shaped member 107 when it is not to be used and swung backward and upward as described. The construction which has just been described is essential in maintaining the trapeze landing platform against undesired swaying or swinging movements due to the wind when it is mounted upon the trolley carriage in position for an airplane to land thereon. The trapeze landing platform is suspended at the inner sides of the 100 described structure, as shown in Fig. 60, when it has been lowered from its engagement with the fingers 108 on the tubular members 107 to engage with the bar 83, as previously described, the horizontal members of the trapeze landing platform lying below the lower points of the hooks 167 and 168 so that the same will not interfere in any respect with the trapeze landing platform when the airplane engages there- 105 with and moves the platform away from the hooks in an upward lateral swinging movement. There will be no swinging movement of the landing platform outwardly by reason of the wind, and wind, 115 if any, tends to move the trapeze construction and holds it against the bars 162. The springs 161 normally swing the construction to do so or until the stops 159 and 160 engage with each other and are strong enough to overcome any tendency of the wind to move said construction in a reverse direction. Gravity also aids in maintaining the construction in proper position.

When the trapeze landing platform is 120 disengaged from the trolley carriage and lifted therefrom the horizontal members of the landing platform are raised against the horizontal portions of the hooks 167 and 168, or from the full to the dotted line 130.

position as shown in Fig. 63, and then when the motor 172 is operated to lift the construction to the horizontal inoperative position shown in Fig. 60 the landing platform 5 is carried by the hooks and moved out of the way and will remain out of the way until again lowered for the purpose of landing an airplane thereon.

The stabilizing structure described is very 10 useful for maintaining the landing platform against swinging or swaying movements or any other movements which might occur and for maintaining the landing platform in proper position that the landing 15 hook on the airplane may engage therewith; and also for lifting the trapeze landing platform out of the way when it is not to be used.

The trolley carriage, indicated as a 20 whole by reference character 79, and which, as has been described, carries the horizontal tubular member 83 supported by the diagonal downwardly extending tubular members 82, includes in its construction two 25 spaced apart upper horizontal bars 176, likewise located in the same but an upper horizontal plane, at the ends of which are bumper plates 177 and 178. The tubular bar 83, previously described, lies between their 30 ends and is connected thereto and supported thereby by means of supporting brackets 179. The bars 175 and 176 are also of tubular construction for purposes of strength and lightness in construction. The bars 175 35 and 176 are associated with a plurality of flat vertical frame bars 180 and 181 connected thereto by suitable brackets, the vertical side bars 180 and 181 being connected at their upper ends by an integral cross 40 member 182 which passes between and over the upper bars 176. See Figs. 38 and 39. Upper rollers 183 below which are other rollers 184, are mounted on the tubular members 176 of the trolley carriage by means of 45 suitable bearings and brackets, as shown in Fig. 38. Likewise similar rollers 183a and 184a are located at the lower portion of the trolley frame and at each end thereof. The trolley carrying cable 76 at its upper run 50 passes underneath the rollers 183 and over the rollers 184, while at its lower run it passes over the rollers 183a and under the rollers 184a. The plate 178 at the outer and upper portion of the trolley carriage carries 55 diverging guide members 185 (Fig. 37) between which the rollers 125a on the part 125 pass when the trolley carriage is moved toward the operator's or flight controller's platform. (Figs. 25 and 26.)

60 The trolley carriage at the end thereof nearest to the platform P, (Figs. 1, 2, 35, 31, and 43) at its lower side is equipped with a depending post 186 which is connected by braces 187 with the opposite end members of 65 the carriage 180. The post 186 at its lower

end is equipped with a collar 188 (Figs. 35, 36, 39 and 43) from which a pair of supporting bars 189 extend downwardly. Fixed arms 190 extend from the lower ends of the bars 189 and a fixed horizontal arm 191 extends substantially at right angles to each pair of bars 189. A hook 192 is pivotally mounted between the lower ends of each pair of bars 189 and has an arm 194 extending therefrom to which one end of a link 195 70 is pivotally connected. The hook 192 is adapted to engage with the suspending members 80 extending upwardly from the upper wing or fuselage of the plane, as illustrated in the drawings, and when in the position shown in Figs. 35 and 36 and 43 serves to connect the rear portion of the plane wing or fuselage to the trolley carriage. 75

At the other end of the trolley carriage 80 is a depending hollow post 196 having a collar 197 permanently secured at its lower end (Fig. 41). Supporting bars or a stirrup 198 similar to the bars 189, previously described, extends downwardly from the post 196 and it likewise has downwardly extending fixed arms 199 which are connected at their lower ends by a bar 200 to the lower end of the post 196 at the opposite end of the trolley carriage. There is a horizontal arm 201 secured to the stirrup 198, associated with which is a hook 202 pivotally mounted on and between the lower ends of the stirrup. The hook 202 is formed at the outer side of an arm 203 which at its free end has an engaging finger 204 (Fig. 41) spaced from 100 which is a second and longer finger 205. From the arm 203 at the pivot end two other arms 206 and 207 extend at an angle to each other to the former of which the bar 195 is connected, that is, the bar 195 connects 105 the outer ends of the two arms 194 and 206 whereby suspending hooks 192 and 202 are joined together and are operated simultaneously. The hooks 202 serve to engage with the other suspending elements 80 adjacent 110 the front edges of the upper wings or fuselage of the plane. Accordingly, when both of the suspending elements 80 are engaged with the hooks 192 and 202 and said hooks 115 are in their upper positions against their guards 191 and 201 the plane is connected securely with the trolley carriage and cannot disconnect therefrom as long as the hooks 192 and 202 are in such positions. But upon the automatic release of the arm 203 from the holding device 215 therefor, 120 which engages with the finger 204. (Figs. 41, 47, 48 and 49) as will hereafter appear, the hooks 192 and 202 are forced by the weight of the plane suspended thereon and spring 210 attached thereto to turn in a downward direction away from the guards 191 and 201 and alongside the fixed arms 190 and 199 which serve to force the suspending elements 80 from the hooks and free the 125 130

plane from the trolley carriage at the proper time for flight, the take-off of the plane from the trolley being automatically controlled and determined by the location of the trip 5. T3 on the control line 77, as will hereafter be described.

The post 196, a distance above its upper end, is fixed to the lower end of a sleeve 208a above which is a horizontal arm 209.

10. A coiled tension spring 210, connects the arm 209 and the previously described arm 207, from the full line to the dotted line position shown in Fig. 41, so that when the finger 204 is released, as hereafter described, in 15 conjunction with the weight of the plane to swing the arm 207 and the hooks 202 in a direction to release the hooks from the suspending elements 80 on the plane, and at the same time the hooks 192 through the 20 connecting links 195. Arm 207 acts as a stop (Fig. 41) to limit the throw of the arm 208.

A heavy coiled compression spring 211 is located around the post 196, its upper end 25 bearing against said flange 208a. At its lower end it surrounds a sleeve 212, mounted for sliding movement on the post 196, and bears against an outwardly extending annular rib or flange 212b on the sleeve, underneath which a gear segment 214 and a latching member 215 connected together are mounted for partial rotation around the sleeve 212, the same being carried with said sleeve 212 in its upward movement through 30 the ring rod 296 and collar connection 212a. See Figs. 36 and 50. The latching member 215 is of a shape that the finger 204 may engage therewith when the lower end of the sleeve 212 bears at its lower end 35 against the collar 197 (Fig. 41).

When the member 269, see Fig. 35, contacts with the trip T-3, the shaft 264 is rotated and the track 297 is shifted past the horizontal thus causing the roller 298 to travel 40 theralong due to the action of the spring 300. This action forces bar 279 until the end of the slot 290 strikes the pin 292 thus actuating the vertical rod 296 through the lever pivoted at 293. The movement of the 45 rod 296 operates the plane releasing mechanism. Further description of the operation of this mechanism will be set forth later in the specification.

An arm 221 extends radially from the collar which carries the segment 216 on which an electrical contact 222 is secured, depending therefrom. An electric circuit wire 223 is connected with said contact. A fixed arm 224 (see Fig. 52) extends outwardly from 50 the collar 197 and at its outer end is connected with a collar 225 located around the lower end of the shaft 217 from which an arm 226 extends outwardly, carrying an upwardly extending electrical contact 227 with 55 which a second circuit wire 228 is connected.

Said contact 227 is adapted to have electrical engagement with the previously described contact 222 when the arm 221 is positioned directly above the arm 226, thereby signalling to attendant on platform T that 70 the plane is locked to the trolley carriage.

The shaft 217, adjacent its upper end, is provided with a coiled torsion spring 229 (Figs. 35 and 36) the tendency of which is to turn the same so as to bring the two contacts 222 and 227 apart. See Fig. 42. The upper end of the shaft 217 is equipped with a gear segment 230 (Fig. 41) which meshes with a segment 231 at one end of an arm 232 pivotally mounted on the frame of the trolley carriage to turn about a vertical pivot 233. The opposite end of the arm 232 is forked, the forks 234 passing above and below (Fig. 35). A hub or drum 236, as will later appear, is slidably mounted on a cross shaft 264 carried by the frame of the trolley carriage, said shaft also serving to mount other mechanism. The ends of the forks 234 (Fig. 44) connected by a vertical rod 237 which passes through one end of a second bar 238, is pivotally mounted between its ends at 239 on a vertical pin carried by the trolley carriage. The free end of the bar 238 is equipped with a downwardly extending cylindrical plug 240 which (see Fig. 95 55) may pass between two spaced apart upwardly extending arc shaped lugs 241 projecting from a sleeve 243 slidably mounted on a transverse shaft 242 and held from rotation by a key 242a.

The sleeve 243 is provided with an integral upwardly extending arm 244 and with a downwardly extending finger 245 which may engage against a stop 246 on the trolley carriage, to properly locate the arm and sleeve when manually moved into position shown in Figs. 53, 54 and 55. The transverse shaft 242 has a torsion spring 242d encircling it, and by means of a fixed stop 242c on the trolley carriage and stop 242b on the shaft 242 resisting its torsion pressure, said spring 242d holds the finger 245 firmly against stop 246. At the upper end of the arm 244 an operating finger 247 is pivotally mounted on a vertical stud 248 actuated by a torsion spring 249 to normally bring the finger against a stop 250 at the upper end of the arm 244.

Shaft 242 at its end at the opposite side of the trolley has a sleeve 251 secured thereto from which an arm 252 extends upwardly divided at its upper end to provide spaced apart forks 253. Two downwardly extending arms 254 depending from a horizontal bar 255 pass, at their lower ends between the forks 253 and are pivotally mounted thereon on a pivot pin 256 (see Fig. 55). A coiled spring 257 around the pivot bears at one end against a stop 258 on one of the arms 254 and at the other end against a 130

stop 259, the tendency of the spring being to turn the arms 254 into direct alignment with the member 252. One of the arms 254 is provided with a downwardly extending 5 dog 260 which in its normal position, as shown in Fig. 56, is brought against the stop pin 259 previously mentioned. The bar 255 at one end is equipped with a head 261 which in vertical position engages with the 10 lower end of lever 262 (see Fig. 38), whereby when the same is swung outwardly through engagement with incline 125b (Fig. 26) cable grip members 285 and 288 (Fig. 58a) are opened and held open, releasing 15 them from friction contact with the moving cable, until finger 247 engages with trip T² and shaft 242 is thereby partially revolved, carrying stop 261 out of engagement with the end of the clutch operating arm 20 262, as shown in Figs. 53a and 54, thereby automatically releasing the gripping dogs 285 and 288 on the top run of cable 76.

The sliding hub or collar 236 is located over the key 263 pinned or otherwise secured to a horizontal shaft 264 mounted on 25 and between the sides of the trolley carriage, splicing the hub on the shaft (see Fig. 45). At one end of the key 263 a collar 265 is fastened to the shaft 264, holding 30 a flanged idler wheel 266 between it and a collar 264a pinned to the shaft 264 at the opposite side of the idler wheel 266. The idler wheel 266 serves to support the trolley control line 77, as shown in Fig. 44.

35 On the hub 236 at one side thereof a member 267 extends radially parallel to the sides of the idler wheel 266 for a short distance and is then turned substantially at right angles to make a finger 268 which extends 40 outwardly beyond the edge of the wheel 266. A spring shock absorbing finger 269 is secured to the arm 267 at the inner side of the rigid finger 268 and extends in the same direction and its free end follows the same 45 curved path of movement as does the rigid finger 268. A duplicate construction is connected with the collar 264a which is fastened to the shaft 264, including an opposite radially extending part 270 having rigid and 50 spring fingers 271 and 272 turned substantially at right angles therefrom and being substantially parallel to the fingers 268 and 269 but spaced therefrom with the idler wheel 266 between, the outer ends thereof 55 following the same circular path of movement as the ends of fingers 268 and 269. Said fingers 271 and 272 are always in alignment with the trip T¹ while the fingers 268 and 269 are in alignment with the trip T³ when plane is attached to trolley carriage 60 for take-off and out of alignment therewith when plane is attached to a trapeze landing platform through a hooking landing thereon. It is evident that the fingers 268, 269, 271 and 65 272 are operatively connected with the shaft

264 and turned therewith or vice versa, serving to turn the shaft when actuated. The spring finger 269 serves as a shock absorber in order that there will not be too abrupt a 70 rotative movement imparted to the shaft 264 when the engagement with the trip takes place. In other words the rotation of the shaft 264 occurs only at predetermined times when there is engagement of the fingers described with the trips T¹ and T³ located at 75 proper position in the length of the trolley control line.

The spring finger 269 engages only with T³. As shown in Fig. 35 such engagement 80 revolves the shaft 264 anticlockwise and the spring 300 acting upon the roller 298, which in turn rolls upon the track 297, completes this movement thus quickly releasing the plane when at its flight speed. At the same 85 time the clutch grip on the top run of cable is released and the bottom cable is gripped by the reverse clutch thus checking, stopping and then returning the trolley to the left. The operator now takes control of the trolley. 90

At one side of the trolley (Figs. 36, 39, 39a and 40) midway between the ends of the bar. A link 274 is connected with one end of the bar 273 (Fig. 36), said link at its upper end being pivotally connected at 275 95 (Fig. 39a) to an elongated vertically positioned clutch operating bar 276, (Fig. 39b) while the other end of the bar 273 is similarly link connected by a link 277 to a second clutch operating bar 279, the link 277 having pivotal connection at 278 to the second bar 279. Both of the bars 276 and 279 are formed with off-set spring inclined portions 280 projecting toward the frame structure of the trolley (Fig. 39b). 100

The bars 276 and 279 ride against rollers 281, see Figs. 39, 58, 58a and 59, which are mounted in suitable bearings carried at the outer ends of projecting brackets 281a fixed to the adjacent bars 175 and 176 of the trolley. The upper end portion of the upper bar 276 rides against the upper roller 281 (Fig. 39) while the lower end portion of the lower bar 279 rides against the lower roller 281 as shown. 110

The bars are additionally guided by suitable horizontally extending guides 282 extending outwardly from the vertical member 180, shown in Figs. 36 and 39 at the adjacent sides of the trolley. The inner sides of the bars 276 and 279 are pressed against by rollers 283 mounted at the ends of clutch carrying slides 284 which are movably mounted for longitudinal movement on the rods 176 and 175. The clutch carrying members 284 has a brake shoe 285, 285a of substantially semi-circular form secured thereto and lying at one side of the cable 76 as shown in Figs. 58, 58a and 59. The clutch carrying members 284 are made in two sec- 120 125 130

tions bolted together for the insertion of the endless cable therethrough and to permit a limited longitudinal movement of the members 284 and are normally acted upon by 5 coiled compression springs 286 around rods 287 extending inwardly from the opposite side bars 175 and 176 the tendency of which is to move the clutch carrying members in a direction so as to disengage and move the 10 brake shoes 285 a short distance away from the cable 76; but upon proper rotation of the shaft 264 so as to alternately bring the spring inclined portions 280 on either bar 276 or 279 against the rollers 283 the brake 15 shoes 285 are moved to engage with the cable 76 and press the same into engagement with the fixed clutch shoes 288, 288a, at the opposite sides of the cable. The fixed clutch shoes are permanently secured to bracket 20 arms 289 which in turn are connected to the rods 175 and 176 at the side of the trolley opposite where the rollers 281 and 283 are located.

The lower end of the bar 279 (Figs. 36, 25 36a, 36b and 39a) is longitudinally slotted as indicated at 290. An arm 291 has a pin 292 extending into the slot of said slotted section 290 and is secured at its other end to a rock shaft 293 mounted at the lower end 30 of supporting bars 294 which extend downwardly from and are connected at their upper ends to the lower tubular members 175 of the frame of the trolley. A second arm 295 is secured at one end to the rock shaft 293 and has a pivotal connection at its opposite end to a rod 296 which, as shown in Fig. 41, passes downwardly in the tubular member 196, the rod 296 connecting at its lower end to the sleeve 212 whereby on the 35 downward movement of the bar 279 after the movement has progressed sufficiently that an engagement with the pin 292 is made, arm 291 is depressed and arm 295 is elevated and the sleeve 212, see Figs. 41, 42 and 51, 40 with the connecting latch 215 lifted, causing a disconnection of the latch from the locking pin 204 on arm 203, thereby shoving the plane off of the trolley during its take-off. It will be noted that the engagement of the 45 50 brake shoes 285 and 288 with the lower run of the cable 76 occurs when the bar 279 is moved downwardly, this being accompanied by simultaneous upward movement of the bar 276. Therefore an operation which 55 causes the engagement of the clutch shoes with the upper run of the cable is never accompanied by a setting of the lower clutch shoes against the lower run of the cable or vice versa. And it is only on the downward 60 movement of the bar 279 that any automatic unlatching of the latch 215 from engagement with the arm 203 can occur (Fig. 41).

As previously described the bar 273 (Figs. 35, 36, 29 and 29a) is secured to one end of 65 the shaft 264, at the opposite end of the

shaft a bar 297 having a triangular shaped upper edge is mounted on a U-shaped support 297a which is secured directly to the end of the shaft 264. A grooved roller 298 is mounted to traverse the upper edge of 70 the bar 297, a U-shaped stirrup 299 (Figs. 38 and 39) carrying the roller and depending therefrom, one side of the stirrup extending between the two bars 297 and 297a so that the roller is stopped in its travel 75 when the stirrup engages against the lateral connecting portions at the ends of the two bars 297 and 297a. A tension spring 300 is secured at one end to the stirrup 299 and at the other end to a suitable arm 200a fixed 80 to the adjacent lower tubular member 175. This construction is for the purpose of snapping the shaft quickly from one position to another, it being evident that when the shaft is turned in either direction by the engagement of the fingers 268 and 269 or the fingers 271 and 272 with trips T² or T³ alternately on the trolley control line, see Figs. 39, 39a and 44, the force of the spring 300 will resist the rotation until the bar 297 has 85 reached an angle above a horizontal position whereupon the force of the spring will aid such rotation and cause it to be carried through quickly; and will thereby through its related parts, as previously described, on 90 the opposite end of shaft 264 reverse the clutch shoes from the top cable strand to the bottom cable strand or vice versa.

In landing the plane the detachable trapeze platform having first been attached 100 to the trolley, the trapeze platform and trolley are at the left end of the structure (in Fig. 1) and the trolley is free of the speeding cable 76, the upper run of which moves toward the left and the lower run toward 105 the right, as indicated by arrows in Fig. 1. The superstructure above the aerodrome is readily turned by the motors 7 and the gearing connections between them and such superstructure so as to locate the structure so 110 that the plane heads into the wind when landing. The pilot releases the landing hooks prior to engaging with the landing trapeze platform and the same will extend upwardly and to the rear from the fuselage 115 and the hooks will engage with the landing platform 93 and automatically lock therewith.

The trolley rests idly upon the cable and 120 will start toward the right (Fig. 1) having its initial inertia overcome due to the swing of the plane and to the cushioning action of its landing on the cushioning trapeze platform. The trolley will be drawn toward the right until the trip T² is reached which 125 serves to automatically release the clutch shown in Fig. 58a to grip the upper run of the speeding cable 76 and thereupon apply friction to decelerate and check the speed of movement of the trolley and the plane 130

attached thereto, with a resultant bringing the plane to a stop within a limited distance; and the automatic and manual speed controls for the cable, illustrated in Fig. 29a 5 in conjunction with Fig. 29, lessen its speed from time to time automatically as the plane and trolley carriage move toward the right.

The cable 76 is operated to draw the trolley with the attached plane back to the left 10 side of the structure (as shown in Fig. 2) and the trolley is then latched on the member 125, the trapeze landing platform being disengaged from the trolley and swung out of the way and held underneath the plat- 15 form of the attendant.

In launching the plane the engine is started and it is warmed up and when in proper condition for running at the speed desired by the pilot, on signal from the pilot to the 20 attendant, the latching connection holding the trolley carriage is released whereupon the trolley and plane start to the right, see Fig. 2, while the cable clutch is released to grasp the cable 76. The cable is automatically accelerated as the plane and trolley move farther to the right and finally, before the right hand bumpers at 81 are reached by the trolley, trip T3 is reached and through the mechanism controlled thereby 25 on the trolley the cable clutch is released and reversed to clutch the lower run of the cable and at the same time the latch mechanism, shown in Figs. 35 and 36, connecting the plane to the trolley is automatically released freeing the plane from the trolley, the plane having attained a speed sufficient that it may be freed to continue in the air without danger of not being able to maintain flying speed. The simultaneous auto- 30 matic engagement of the lower cable clutch with the lower run of the trolley operates to frictionally check the trolley speed so that no damaging effect will occur by reason of its momentum should it be carried against 35 the spring bumpers 81.

At the time of landing, the arm 262 is in the position shown in Figs. 38 and 55, thus holding the gripping dogs 285 and 288 off of the cable 76. See Fig. 37. The trolley 40 is locked in position by the arm 302 (see Figs. 35 and 36) engaging with the locking stop 125c, (see Fig. 26). The top run of cable is speeding to the right as indicated by the arrow in Fig. 2.

The trolley construction described is adapted to serve many important functions. It supports the trapeze platform on which the pilot makes a hook-on landing. This has been fully described and is illustrated 45 in Figs. 1, 17, 21 to 27 inclusive, 60 and 61.

It carries, also means for locking the plane on and releasing the plane therefrom as has been fully described with reference to Figs. 2, 35 to 38, 40 to 42 and 47 to 52.

C3 It carries a means for gripping automati-

cally by releasing and operating a spring actuated clutch, the top and bottom runs of the cable at proper times as illustrated in Figs. 35, 36, 38, 58, 58a and 59. It carries means to be operated in conjunction with the trips T¹, T² and T³ on the control line 77 (Figs. 1, 2, 29, 29a and 44) for releasing the cable clutch, and for reversing the engagement of said clutches from and on said cable runs simultaneously with the release of the plane from the trolley thereby checking and largely, if not entirely, stopping the trolley before the contacts with the bumpers 81. It carries means for holding the clutch from the upper run of the cable for a short period of time at the beginning of the hook-on of an airplane with the trapeze platform, and has means operated in conjunction with the trip T² on the control line 77 for releasing and gripping said upper run of the cable (Figs. 35, 36, 39 and 40 inclusive and 53 and 57 inclusive), thereby making provision for the plane in landing to overcome the inertia of the trolley before the effect of the opposite movement of the cable is applied through clutching the cable when the trip T² is reached.

It carries a means (the arm 302, Figs. 35 and 36) in conjunction with the manually operated lever shifted latch 125 for locking the trolley and a plane connected therewith adjacent the platform with the cable clutch free from the cable while the pilot tunes up the motor prior to taking-off and at the pilot's signal to release the plane, whereby, on said plane's release, the arm 302 is spring actuated on raising the lever 127 to release the latching member 125 (Fig. 26) which is lowered below the end of member 302 whereby releasing the cable clutch to grip the top cable run (as in Fig. 2), thereby accelerating the plane through the force exerted by the cable in conjunction with the engine on the plane.

The trolley also carries means in conjunction with the control line 77 (Figs. 1, 2, 29, 29a and 44) whereby the cable speed is automatically increased as the trolley speeds away from the platform P through the switch contacts S, S¹ attached to the trolley, thereby governing the current through the automatic rheostat 123 for controlling the cable speed when the plane takes off; and a similar rheostat switch 124 for checking and stopping the plane when it lands. The upper cable moves in a direction opposite the flight of the plane when the plane lands, the cable speed being automatically controlled by the position of the trolley in the length of the cable, while in taking-off the cable runs in a direction opposite to its direction in checking the plane. It further carries a releasable locking means for holding and automatically releasing and disconnecting the plane attached thereto at a

predetermined point in the length of the cable, together with means, simultaneously with such act of release, for shifting the cable clutch from the top cable to the bottom cable. The attendant of the mechanism on the platform P thereafter, through the control provided by switches 121 and 122, and cable control rheostat 120 may move the trolley to any place desired in the length of the cable.

Without recapitulating all of the functions of the structure, it is apparent that a landing and take-off mechanism is provided through which either the landing or the launching of an airplane may be effectively operated and the same properly controlled within a limited space or length, thereby doing away the necessity of large landing fields which must be located at a considerable distance from the centers of cities and the like.

With my invention the apparatus can be used on the roofs of buildings directly in the business sections of cities, or in a great many other places as previously stated. Checking the plane by the control of the endless cable when it is landing, or accelerating its speed, in a very short distance, when it takes off, is a very valuable feature of the present invention. The various controls for rendering the operation largely automatic are also of value in the invention. The invention is defined in the appended claims and is to be considered comprehensive of all forms to structure coming within their scope.

I claim:

1. A construction of the class described, comprising an endless, movable track element, a carriage supported thereon, and means below said carriage for connecting an airplane thereto.

2. A construction of the class described, comprising an endless, movable track element, a carriage supported thereon, and means for connecting a landing airplane thereto, through said plane have co-ordinating means for support thereon, and at a predetermined distance from all contacting surfaces.

3. A construction comprising the elements in combination with claim 2, and means on said carriage for frictionally gripping said carriage, to said endless, movable track element.

4. A construction comprising the elements in combination with claim 1, and means on said carriage for frictionally gripping, as required, one of the two runs of said endless, movable track element.

5. A construction comprising the elements in combination with claim 1 and co-acting means with said endless movable track element, and said carriage, for automatically releasing the carriage's frictional grip on

one run of said endless movable track, and automatically gripping the second element in opposite direction of travel of said endless movable track element.

6. A construction comprising the elements in combination with claim 1 and co-acting means with said movable track element and said carriage for automatically controlling the speed of said endless movable track element in relation to the position of the carriage in the length of said movable track element. 70

7. In combination, an endless movable track element, a carriage thereon, a control line, releasable means on the carriage adapted to support an airplane and releasable means on said control line at a predetermined point in the travel of the carriage, between pulleys supporting said movable track element. 75

8. The elements in combination, as recited in claim 7 and supplemented by additional means for releasably holding the airplane to the carriage and means to simultaneously release both sets of releasable means. 80

9. In combination, a support, means movably mounted thereon to travel longitudinally on said support, detachable means adapted to contact with an airplane during its landing manipulations, removably mounted on said moving means, and means for removing and supporting said detachable means. 95

10. A construction containing the elements in combination with claim 9 combined with a member adapted to be permanently fixed to the movable means to support an airplane during its take-off. 100

11. In a construction of the class described, two spaced apart supports, a track therebetween, a trolley adapted to traverse the track, means to connect an airplane to the trolley, adjustable speed means to move the track longitudinally, clutch means to grip the trolley to its track, a control support extending between the supports, means on the support adapted to operate the clutch means at predetermined intervals and additional means on the support adapted to contact with trolley to govern the speed of the adjustable speed means, said additional means and said adjustable means being electrically actuated and controlled from a common source. 110

12. Means for landing airplanes comprising a cable, a carriage movably supported thereby, flexible trapeze means depending from the carriage and stabilizing means adapted to contact with the trapeze means. 120

13. A device of the character described, consisting of two spaced apart supporting pulleys, means for revolvably supporting said pulleys about their respective axes and at a considerable vertical and transverse distance from any contacting surfaces, a flexible track element, adapted to be cooperatively asso- 125

- ciated with said pulleys, a carriage movably supported on said flexible, track element, frictional gripping means located on the carriage adjacent the track element, a fixed control line adjacent to said track element and means on the said control line for operating the aforesaid, frictional gripping means whereby the carriage is gripped to the track element.
- 10 14. An airplane landing and take-off apparatus comprising two spaced apart pulleys, a flexible track element encircling said pulleys, a carriage movably supported on said track element, means on the carriage adapted to engage with said flexible track element, gears, rigid with, and concentric to the aforesaid pulleys, two spaced apart pinions meshing with said concentric gears, and means to drive said pinions.
- 15 15. Means for landing airplanes comprising a carriage, a carriage supporting flexible track and coordinating landing means below said carriage, means for supporting said flexible track, base means for revolvably supporting said track supporting means, and electrical means to revolve said base means, and means, actuated by the wind, adapted to automatically actuate the said electrical means.
- 20 16. A combination, as described in claim 15 and having further means adapted to lock said revoluble means, in fixed position.
- 25 17. In the construction of the character described for decelerating and accelerating airplanes, through cumulative electric means, reacting on a movable carriage supported on a straight-away track element, located a suitable distance from all vertical and contact surfaces, of an elevator adapted to raise and lower said airplane for take-off and parking purposes, said elevator means being located between means supporting said carriage and foundation means supporting said track element.
- 30 18. In the construction of the characters described in claim 17, a roof, having an opening, therethrough, beneath said elevating means, hinged sides and end members, in the vicinity of same, and adapted to swing from a horizontal, to a vertical position, and vice versa, thereby forming a wall or enclosure, or temporary wind-shield for safeguarding said airplanes.
- 35 19. A superstructure of the character described in claim 17, adapted for installation and use upon bridges, viaducts, buildings, and the like, comprising an airdrome having an upper cylindrical track, a cover therefor, means for revolvably mounting the cover over the airdrome, and an overhead airplane, launching and landing apparatus, supported by said revoluble cover.
- 40 20. In combination, a support, a carriage mounted thereon, and means for connecting a landing airplane thereto, through said plane having coordinating means, for support thereon, and means on said support means, for killing said airplane's engine, at instant of contact therewith.
- 45 21. In a device of the class described, adapted to receive a moving airplane thereon, the combination of, a track element, means for supporting said track element in parallelism with the path of the airplane which is landing thereon, a carriage mounted upon said track element and adapted to move therealong upon contact of the airplane therewith, said carriage and said airplane having cooperating means which are adapted to interlock upon contact therebetween whereby the airplane is fastened to the carriage, and means cooperatively associated with the said carriage whereby its resistance to movement may be controlled.
- 50 22. The combination of elements as set forth in claim 21 but in which the last mentioned means consists of electrical means.
- 55 23. In a device of the class described, adapted to receive a moving airplane thereon, the combination of, a track element, means for supporting said track element in parallelism with the path of the airplane which is landing thereon, a carriage mounted upon said track element and adapted to move therealong upon contact of the airplane therewith, said carriage and said airplane having cooperating means which are adapted to interlock upon contact therebetween whereby the airplane is fastened to the carriage, and means actuated by the contact means to cause the engine of the airplane to cease operation.
- 60 24. In combination, a support, means movably mounted thereon, said means being adapted to travel longitudinally on said support, releasable means on said movable means adapted to support an airplane, braking means coordinating with said movable means and means operated by the longitudinal movement of said movable means to cumulatively increase the resistance of the braking means.
- 65 25. In combination, a flexible support, means movably mounted thereon and depending therefrom to travel longitudinally on said flexible support, releasable means on said movable means, adapted to support an airplane, and fixed means adapted to engage with said releasable means at a set point in its longitudinal travel, to release said releasable means.
- 70 26. In combination with an airplane having supporting means thereon, of a straight-line support, a carriage having a longitudinal movement thereon, and means for connecting the landing airplane thereto, through said supporting means of the plane, and supplemental means for automatically

locking said plane thereto, at the instant of connection between the supporting means and the first mentioned means.

27. In combination, longitudinally supporting means maintained in longitudinal position through its opposite terminals being supported on spaced apart anchoring means, carriage means mounted thereon and depending therefrom and movable between said anchoring means, electrical means to propel said carriage, means to regulate the electrical means, and means controlled by the position of the carriage to control the electrical regulating means.

15 28. In a device of the character described, a supporting means of fixed length between supports, means movably resting thereon and depending below said supporting means of fixed length, said movable means being 20 adapted to travel longitudinally on said supporting means of fixed length, through the momentum of an airplane landing thereon, and means for applying at predetermined positions, to said movable means, in 25 its so determined longitudinal travel on said supporting means, a series of predetermined, cumulative, electrical resistances, to such longitudinal travel of said movable means on said supporting means of fixed 30 length, between its fixed supports.

29. In combination with a supporting means of fixed length, unyieldingly supported, both longitudinally and vertically, at its spaced apart opposite ends, means 35 mounted thereon, adapted to have an airplane releasably attached thereto, at a point below said supporting means of fixed length and cumulative electrical means, for accelerating said plane supporting means, to the 40 plane's flight speed.

30. In combination, a supporting means of fixed length unyieldingly supported, both longitudinally and vertically, at its spaced apart opposite ends, means mounted thereon, adapted to have an airplane releasably attached thereto, at a point below said supporting means of fixed length, and cumulative electrical means, for accelerating said plane supporting means, to flight speed and 45 means to automatically release same therefrom, at a fixed point in its longitudinal movement.

In testimony whereof I affix my signature.
WILLIS J. PERKINS.
